UNITED STATES PATENT OFFICE

112,802

DESIGN FOR A VAMP OF A SHOE

Jack Werman, Brooklyn, N. Y.

Application December 3, 1938, Serial No. 81,559

Term of patent 3½ years

To all whom it may concern:

Be it known that I, Jack Werman, a citizen of the United States and resident of Brooklyn, in the county of Kings and State of New York, have invented a new, original, and ornamental Design for a Vamp of a Shoe, of which the following is a specification, reference being had to the accompanying drawing, forming part thereof, in which the figure is a perspective view of the vamp of a shoe, showing my new design.

I claim:

The ornamental design for a vamp of a shoe, as shown.

JACK WERMAN.
